UNITED STATES PATENT OFFICE.

HENRY N. LOOKER, OF CHICAGO, ILLINOIS, ASSIGNOR OF ONE-FOURTH TO OAKLEY W. PLATT AND THREE-EIGHTHES TO GEORGE W. REYNOLDS, BOTH OF CHICAGO, ILLINOIS.

FILTER.

1,112,923.

Specification of Letters Patent.

Patented Oct. 6, 1914.

Application filed May 15, 1914. Serial No. 838,640.

To all whom it may concern:

Be it known that I, HENRY N. LOOKER, citizen of the United States, residing at Chicago, in the county of Cook and State of Illinois, have invented a certain new and useful Improvement in Filters, of which the following is a full, clear, concise, and exact description, reference being had to the accompanying drawings, forming a part of this specification.

My invention relates to filters and has for its object the provision of a filter of simplified construction and whose interior is readily accessible for the purpose of cleaning and replacement of parts.

In practising my invention I employ a chamber, which is preferably tubular, and which is provided at its ends with means for attaching sections of a feed pipe thereto whereby the chamber itself constitutes a feed pipe section that is alined with the feed pipe sections that are coupled therewith. The cylindrical or longitudinal wall of the chamber is provided with cylindrical bosses for receiving closure caps, one of these bosses affording access to a charcoal or carbon holding compartment and the other affording access to a trap space surrounding a pipe that projects into the chamber toward but short of the carbon containing portion of the chamber. By this construction I have provided a very simple form of filter which may be readily inserted in feed or other liquid conducting pipes without disturbing the alinement of the pipe sections between which the filter is disposed and permitting the formation of a filter to which access may readily be had.

I will explain my invention more fully by reference to the accompanying drawing showing the preferred embodiment thereof and in which—

Figure 1 illustrates a device of my invention as it may be installed; Fig. 2 is a sectional elevation on line 2 2 of Fig. 1; and Fig. 3 is a sectional plan view on line 3 3 of Fig. 2.

Like parts are indicated by similar characters of reference throughout the different figures.

The chamber 1 is desirably cylindrical. The upper end wall 2 has an outsetting hollow cylindrical boss 3 which is threaded upon its interior to receive the lower threaded end of a section 4 of a feed pipe.

The lower end wall 5 has an outsetting hollow cylindrical boss 6 which is threaded upon its interior to receive the upper threaded end of a section 7 of the feed pipe. The tubular chamber 1 is thus adapted also to constitute a section of the feed pipe and serves to couple the feed pipe sections 4 and 7 in alinement as the bosses 3 and 6 are coaxial with the tubular cylinder 1. Insetting annular flanges 8 and 9 are provided for positioning screens 10 and 11, there being desirably a number of layers of wire screen at each flange, which layers are clamped between rings 12 by rivets 13. The screens engage the inner faces of said flanges and the spacing between the screens is filled with granulated or subdivided carbon or charcoal illustrated at 14. The carbon or other filtering medium holding space within the chamber is adjacent the outlet end of the chamber. The cylindrical or longitudinal wall of the chamber 1 is provided with an outsetting hollow cylindrical boss 15 through which access may be had to the spacing between the flanges for the purpose of locating or replacing the carbon between the screens. A displaceable sheet metal disk 16 is provided for holding the carbon in position but inasmuch as this disk 16 would not prevent the passage of water through the boss 15 I thread the exterior of this boss and screw upon it an interiorly threaded cap 17 and interpose between the cap and the end of the boss a packing disk 18 for preventing the leakage of water through the boss. The cap 17 is provided with a nutlike outsetting enlargement 19 to enable the application of a wrench for applying and removing the cap. When the charcoal or carbon is to be replaced the cap 17 is removed and the plate 16 dislodged whereafter the carbon may be withdrawn and replaced.

The lower flange 9 is located far enough above the bottom wall 5 to constitute a trap space in which the incoming water is initially received while on its way through the filtering carbon and the feed pipe section 4 leading to the house service pipes above. To complete the trap partially formed by the portion of the chamber 1 located below the flange 9 I provide a short piece of pipe 20 at the intake end of the chamber 1, this pipe being threaded upon its exterior at its lower end where it is in threaded engagement with an interiorly threaded inset-

ting cylindrical boss 21. The bosses 6 and 21 are co-axial whereby the pipe 20 constitutes a branch of the feed pipe section 7, this branch pipe 20 being inclosed by the enlarged section 1 of the feed pipe. As the pipe portion 20 is thus co-axial with the various feed pipe sections 1, 4 and 7, and as spacing exists between the upper end of the pipe 20 and the lower screen 11, a trap is formed about the pipe 20 for receiving bodies of foreign matter that are discharged over the upper end of the pipe 20 into the trap space between the pipe and the cylindrical wall of the chamber 1. The spacing between the upper end of the pipe 20 and the screen 11 is sufficiently large to permit of the discharge of foreign matter to one side of the pipe 20 and is sufficiently small to prevent ready return of the larger bodies of foreign matter. Thus any fish which may float into the trap may not readily find exit therefrom. The screens 10 and 11 prevent upward passage of some of the foreign matter that will not settle around the pipe 20, while the carbon 14 serves to remove the smaller particles of foreign matter and to purify the upwardly flowing water.

It will be observed that the filtering medium, by filling the chamber adjacent its discharge end, serves definitely to divide the chamber into one portion that is exclusively for the accommodation of the filtering medium and another portion which is exclusively reserved for the trap space whereby all impurities that are collected in the trap space are forced to lodge under the filtering medium so as to be accessible through the opening affording admittance to the trap space.

From time to time the trap should be inspected and cleaned. To this end the lower portion of the cylindrical or longitudinal wall of the chamber 1 is provided with an outset hollow cylindrical boss 22 through which access may be had to the trap space about the pipe 20. I thread the exterior of this boss and screw upon it an interiorly threaded cap 23 and interpose between the cap and the end of the boss a packing disk 24 for preventing the leakage of water through the boss. The cap 23 is provided with a nutlike outset enlarging 25 to enable the application of a wrench for applying and removing the cap.

By constituting the chamber 1 a section of a feed pipe and providing it with means 3 and 6 for placing it in alinement with other

feed pipe sections, I am enabled to form a simple structure with closure caps 17 and 23 for openings in the longitudinal wall of the chamber 1 for the purposes stated. I am aware that trap spaces have been provided for retaining larger bodies of foreign matter but there is no device with which I am familiar that is of the simple construction and which so readily affords accessibility to the parts thereof as that which embodies my invention.

Having thus described my invention I claim as new and desire to secure by Letters Patent the following:—

1. A filter including a chamber that constitutes a pipe section and having end walls constructed for the attachment of other pipe sections thereto; a filtering medium confined within the chamber adjacent the discharge end thereof; a pipe within the chamber at the intake end thereof and through which liquid is passed into the chamber, spacing intervening between the inner end of this pipe and the filtering medium and between the pipe and the longitudinal wall of the chamber whereby the pipe and the adjacent portion of the chamber coöperate to form a trap, longitudinal wall portions of the chamber having openings in position to afford access to the space of the trap and to the space that contains the filtering medium; and caps for covering said openings.

2. A filter including a chamber that constitutes a pipe section and having end walls constructed for the attachment of other pipe sections thereto; a filtering medium confined within and filling the chamber adjacent its discharge end; a pipe within the chamber at the intake end thereof and through which liquid is passed into the chamber, spacing intervening between the inner end of this pipe and the filtering medium and between the pipe and the longitudinal wall of the chamber whereby the pipe and the adjacent portion of the chamber coöperate to form a trap whose space does not extend above the filtering medium, a longitudinal wall portion of the chamber having an opening below the filtering medium in position to afford passage from the space of the trap; and a closure for covering said opening.

In witness whereof, I hereunto subscribe my name this 13th day of May, A. D. 1912.

HENRY N. LOOKER.
